Primary Examiner — Ian Simmons*Assistant Examiner* — Dana L Meyrow*(74) Attorney, Agent, or Firm* — Vedder Price P.C.**CLAIM**

The ornamental design for container with lid, as shown and described.

DESCRIPTION

FIG. 1 is a top, front, left side perspective view of a container with lid showing my new design.

FIG. 2 is a front elevation view thereof.

FIG. 3 is a back elevation view thereof.

FIG. 4 is a left side elevation view thereof.

FIG. 5 is a right side elevation view thereof.

FIG. 6 is a top plan view thereof, shown at a reduced scale; and,

FIG. 7 is a bottom plan view thereof.

The broken lines shown in the drawings are for environmental purposes only and form no part of the claimed design.
